RAIL PLOW FOR DISMANTLING RAILWAY TRACKS

John W. Boyle, McClellandtown, Pa., assignor to United States Steel Corporation, a corporation of New Jersey

Application October 18, 1955, Serial No. 541,161

8 Claims. (Cl. 254—104)

This invention relates to an apparatus for dismantling railway tracks and, more particularly, is directed to simplified mechanism in the form of a plow which can be pulled by a tractor or other traction vehicle to dismantle the spiked connections of railway rails to their supporting ties.

One of the objects of this invention is to provide a rail dismantling apparatus for the recovery of railway rails which are secured by spikes to wood ties embedded in the ballast of a railway roadbed. In a manner to be described, the dismantling apparatus includes a draft or cross bar for operating a pair of laterally spaced plows to simultaneously dismantle the spiked connections of a pair of rails with a single supporting cross-tie. The draft bar is provided with a hitch for connection to a tractor or other traction vehicle and by which it may be pulled forwardly along the rails to be removed with its laterally spaced plows sliding along the under surfaces of the rail flanges. The plows have a vertical wedge shape such that their forward movement by the draft bar forces them between the rails and the cross-tie with a wedging action which is effective to elevate the rails relative to the cross-tie and to thus pull the fastening spikes at least partially out of fastening engagement in the cross-tie.

Another object of the invention is to provide a rail dismantling plow of the character referred to with a horizontal wedge shape which operates to spread the fastening spikes laterally out of engagement with the rail flanges after its vertical wedge shape has operated to elevate the rail relative to the cross-tie.

A further object of the invention is to provide a draft-bar support for dismantling plows of the character referred to above which follows the plows through the space between the rails and the cross-tie and in so doing effects final removal of the fastening spikes from the cross-tie.

Other objects and advantages of the invention will be apparent from the following description.

In the drawings there is shown a preferred embodiment of the invention. In this showing:

Figure 1 is a perspective view of the rail dismantling plow of this invention:

Figure 2 is a fragmentary perspective view showing the position of the plow of Figure 1 relative to a pair of railway track rails and a supporting cross-tie during operation to dismantle the spiked connections of the rails to the cross-tie;

Figure 3 is an end elevational view looking from the left of Figure 2; and

Figure 4 is a sectional view taken substantially along the line IV—IV of Figure 3 after movement of the plow draft bar to a position adjacent the rail spikes.

In Figure 2 of the drawings, the numeral 1 designates a wood cross-tie which is embedded in the ballast (not shown) of a railway road bed. Parallel rails 2 are secured to the tie 1 by spikes 3 on opposite sides of each rail. The spikes 3 have heads 4 which engage and clamp the rail supporting flanges 5 against the cross-tie.

2

The dismantling device of this invention includes a draft or cross bar 8 which in operation is placed below the rails 2 in a position extending transversely thereof. The ends of the draft bar 8 extend beyond the outer edges of the rails 2 and have guide blocks 9 welded thereto for sliding engagement with the outer edges of the rail flanges 5 to guide its movement with respect thereto. A pair of U-shaped straps 10 are welded to the draft bar 8 at points inwardly of the rails 2 and furnish connections for attachment to a tractor hitch designated as a whole by the numeral 11 in a manner to be described. The outer leg 12 of each of the U-shaped straps 10 is adapted to have sliding engagement along the inner edge of one of the rail flanges 5 and thus cooperates with the guide blocks 9 in guiding the movement of the draft bar 8 along the bottom of the rail flanges 5.

20   A pair of rail dismantling plows or wedges 13 are rigidly secured as by welding to the draft bar 8 at laterally spaced points. The plows 13 extend forwardly in the direction of movement of the draft bar 8 by the draft hitch 11 and are respectively arranged centrally of the rail flange engaging guides 9 and 12 so that their movement is guided along the under surface of the rail flanges 5. Each of the plows 13 has a flat upper surface 14 which is flush with the upper surface 15 of the draft bar 8 so that it will have sliding engagement with the bottom of a rail flange 5. The plows 13 have somewhat the configuration of an inverted flat-iron which provides wedging points 16 at their forward ends. The lateral edges 17 of the flat plow surfaces 14 are curved and diverge rearwardly from the point 16 to provide a horizontal wedge for a purpose to be described. The lateral spacing of the trailing ends of the edges 17 along the edge 18 of the draft bar 10 is greater than the width of the rail flanges 35 5 for a purpose to be described. The body of each plow has a curvature tapering downwardly from its point 16 to provide a vertical wedging surface 19, as best shown in Figure 3, for a purpose to be described.

The tractor hitch 11 comprises a single strand of cable 20 which has its ends threaded through thimbles 21 and its center portion threaded through a thimble 22. The thimbles 21 and 22 provide eyelets in which a clevis 23 is received, the clevis 23 being adapted for connection with a draw hook (not shown) operated by the driver.

45 with a draw hook (not shown) operated by a tractor or other traction vehicle. The intermediate portions of the cable 20 between its ends and center portion are threaded through thimbles 24 forming eyelets in which the loops of the U-shaped straps 10 are received. Shackles 25 are provided for clamping the cable 20 against movement through the thimbles 21, 22 and 24.

50 In operation, the draft bar 8 is placed under a pair of rails as shown in Figure 2 and the clevis 23 of the hitch 11 is connected to the draw hook of a winch, tractor, or other power operated mechanism for drawing the draft

55 bar 8 forwardly in the direction of the arrow toward the cross-tie 1 as shown in Figure 2. This movement forces the points of the plows 16 between the rail flanges 5 and the cross-tie 1 and continued forward movement to the position shown in Figure 3 is effective through the vertical

60 vertical wedging surfaces 19 to elevate the rails 2 with respect to the cross-tie 1. Elevation of the rails 2 in this manner operates to partially withdraw the spikes 3 from the cross-tie 1. Recalling that the trailing ends of the plow edges 17 along the line 18 have a width greater than the width of the flanges 5, it will be apparent that 65 the edges 17 provide a horizontal wedging action which will spread the spikes 3 apart to the position shown in Figure 4 with their clamping heads 4 out of engagement with the rail flanges 5 as the cross bar 8 is moved to a position with its edge 18 adjacent the spikes 3. Lateral 70 spreading movement of the spikes 3 in this manner is effective to move the spike heads 4 laterally out of holding

engagement with the rail flanges 5. As the draw bar 8 is pulled through the space 26 between the rail 2 and cross-tie 1, its forward edge 18 will engage with and complete the removal of the spikes 3 from the cross-tie 1.

While one embodiment of my invention has been shown and described it will be apparent that other adaptations and modifications may be made without departing from the scope of the following claims.

I claim:

1. A railway track dismantling apparatus comprising a draft bar adapted to be arranged below and extending transversely of a pair of track rails for movement lengthwise thereof, a pair of plows secured to said draft bar in laterally spaced positions and projecting therefrom in the direction of its movement, each of said plows being slideable along the bottom of one of said rails and having wedge means comprising a wedging point at its forward end for entry between such rail and a cross-tie on which it is supported, and wedging edges that diverge rearwardly from said point and are spaced at their trailing ends a distance greater than the width of the rail bottom along which it has sliding movement for releasing the holding connections provided by spikes fastening opposite edges of the rail to its supporting cross-tie.

2. A railway track dismantling apparatus as defined in claim 1 characterized by a pair of guide elements attached to said draft bar for sliding engagement with the sides of the track rails to guide the movement of said draft bar lengthwise thereof.

3. A railway track dismantling apparatus as defined in claim 1 characterized by said wedge means further comprising a vertical wedging surface tapering downwardly and rearwardly from said point for elevating the rails relative to their supporting cross-tie.

4. An apparatus for dismantling the connections provided by railway spikes holding opposite edges of each of the base flanges of a pair of railway track rails clamped against a supporting cross-tie comprising a draft bar positioned below and extending transversely of said rail flanges for movement in a direction lengthwise of said rails, and a pair of plows secured in laterally spaced relation to said draft bar and projecting therefrom in the direction of its movement, each of said plows having a wedging point at its forward end and a flat upper surface extending rearwardly from said point for sliding engagement with the bottom of one of said rail flanges, said flat upper surface having edges which diverge rearwardly from said point and which are spaced at their trailing ends a distance greater than the width of said rail flanges, each of said plows further having a vertical wedging surface tapering downwardly and rearwardly from said wedging point, and draft connections for moving said draft bar lengthwise of said rails to enter said wedging points between said rail flanges and cross-tie and to render said vertical wedging surfaces effective to elevate said rails relative to said cross-tie for partially withdrawing said spikes therefrom and to render said upper plow surface edges effective to spread said spikes laterally out of holding engagement with opposite edges of said rail flanges, said draft bar having portions projecting laterally from said plows for effecting final removal of said spikes

in response to continued movement of said draft bar to a position beyond said connections.

5. An apparatus for dismantling the spiked connection of a railway track rail with a supporting cross-tie comprising a draft bar positioned below said rail for movement along its length in a direction toward said connection, and a plow secured to said draft bar and projecting forwardly therefrom in the direction of its movement, said plow being slideable along the bottom of said rail and having a wedging point at its forward end for entry between said rail and cross-tie and a vertical wedging surface tapering downwardly and rearwardly from said point for elevating said rail with respect to said cross-tie, and wedging edges that diverge rearwardly from said point and are spaced at their trailing ends a distance greater than the width of said rail for dismantling said spiked connection in response to its movement through the space between said rail and cross-tie.

10 6. An apparatus for dismantling the connection provided by railway spikes holding opposite edges of a railway track rail flange clamped against a supporting cross-tie comprising a plow having a flat upper surface for sliding engagement with the under surface of said flange and for movement in a direction along its length toward said connection, said plow having a wedging point at the forward end of said upper surface for entry between said flange and cross-tie and a vertical wedging surface tapering downwardly and rearwardly from said point for elevating said rail relative to said cross-tie, said upper surface having lateral edges which diverge rearwardly relative to each other and have a spacing at their trailing ends greater than the width of said flange whereby they are effective to wedge said spikes laterally out of holding engagement with said flange edges upon movement of said plow along said rail to a position beyond said connection.

20 7. An apparatus for dismantling the spiked connection of a railway track rail to a supporting cross-tie comprising a plow movable along the bottom of said rail toward said connection, said plow having a wedging point at its forward end for entry between said rail and cross-tie, a wedging surface tapering downwardly and rearwardly from said point for elevating said rail relative to said cross-tie, and wedging edges that diverge rearwardly from said point and are spaced at their trailing ends a distance greater than the width of said rail for disengaging said spiked connection.

25 8. An apparatus as defined in claim 7 characterized by said plow having a planar upper surface for sliding engagement with the bottom of said rail, and said wedging point being arranged at the forward end of said planar surface.
